WILLIAM PITMAN, OF NEW YORK, N. Y.

Letters Patent No. 104,641, dated June 21, 1870.

IMPROVEMENT IN COMBINED PUMP AND SIPHON.

The Schedule referred to in these Letters Patent and making part of the same

To all whom it may concern:

Be it known that I, WILLIAM PITMAN, of the city, county, and State of New York, have invented a new and improved Pump and Siphon Combined; and I do hereby declare the following to be a full, clear, and exact description thereof, which will enable those skilled in the art to make and use the same, reference being had to the accompanying drawing forming part of this specification, which drawing represents a vertical section of this invention.

This invention relates to a pump, the suction and discharge-pipe of which form the two legs of a siphon, while the plunger-rod of the pump is provided with a plug, fitting air-tight into the barrel, and the discharge-pipe is furnished with a stop-valve at or near its mouth, in such a manner that, when this valve is closed, a few strokes of the plunger are sufficient to fill both legs of the siphon, and by depressing the plug into the pump-barrel and opening the valve of the discharge-pipe the siphon is started, and any desired liquid can be transferred from one vessel into another with ease and convenience.

The short leg of the siphon is made flexible, and its end is fast to a cord or rope, so that by pulling said cord the leg can be curved upward, and thereby the sediment which may have accumulated at the bottom of the vessel from which the liquid is drawn, is prevented from passing into the siphon.

In the drawing—

The letter A represents the barrel of a pump which is provided with a foot-valve, a, and with a plunger, B, fitted with a valve, b, of any desirable construction.

To this pump is connected a suction-pipe, C, which forms the short leg of a siphon, and a discharge-pipe, D, which forms the long leg of said siphon, and to the mouth of this discharge-pipe is secured a stop-cock or valve, c, so that the same can be opened or closed at pleasure.

From the plunger B extends a rod, d, to the upper end of which is secured a plug, e, which fits air-tight into the mouth of the barrel A, when the plunger is depressed to the position shown in the drawing.

The discharge-pipe may be attached to a tube, f,

extending from the upper part of the barrel, as shown, or it may be connected to the barrel at any convenient point.

In order to start the siphon, I first close the stop-valve c of the discharge-pipe and set the plunger of the pump in motion. After a few strokes with this plunger the siphon is charged. I then depress the plunger, so as to close the top end of the barrel A by the plug e, and prevent the air from passing into the siphon, and then I open the stop-valve c, and the liquid continues to flow through the siphon as long as the mouth of the discharge-pipe is situated below the level of the liquid in the vessel, from which said liquid is drawn.

If the liquid is of such a nature that it is liable to form a sediment, I make the suction-pipe C flexible, and connect it to a cord or rope, g, so that by pulling said cord its mouth can be raised to any desired level, as indicated in the drawing, and thereby the sediment is prevented from passing into the pump, and it is not necessary to hold the whole pump up in order to avoid drawing out the sediment.

If desired, the discharge-pipe may be thrown over a hook or bracket, h, attached to the side of the barrel A, and in this case the pump can be used as a common hand-pump.

What I claim as new, and desire to secure by Letters Patent, is—

1. The plunger-rod a, carrying the plug e, and operating in combination with the barrel A and siphon-pipes C D, substantially as and for the purpose described.

2. The siphon-pipes C D, the stop-cock c, valves a b, barrel A, plunger B, and plug e, combined and operating together to form an improved pump and siphon, as described.

This specification signed by me this 28th day of April, 1870.

WILLIAM PITMAN.
